COIN CARRIER

Harry C. Baller, Los Angeles, Calif.

Application July 26, 1935, Serial No. 33,236

3 Claims. (Cl. 229—92.9)

This invention relates to a carrier for holding coins of one-cent to fifty-cent money denominations, or other similar objects, so that they can be transported and transmitted through the postal system and other similar carriers, safely and economically.

A carrier is made of a foldable material by means of plaits, or infolds, folded at horizontal, perpendicular, acute, and obtuse angles, singly and in multiple, combined, to form a coin inclosure, a supporting frame of infolds, and sections of foldable material, adapted to hold one or more coins, or other similar objects, at approximately the center of the infoldment, and means are provided for holding these infolds and sections in position, carrying out the foregoing object.

It is another object of the invention to provide a carrier that can be easily and economically manufactured by a folding machine, or by hand folding. In machine folding, the machine will mechanically make the folds, or plaits, at predetermined positions of a piece of foldable material to form the coin inclosure, supporting frame of infolds, and sections of foldable material, to hold the coin inclosure in position. In hand folding, impressed, or other markings are adapted to mark the positions of the folds, or start the folds by bending the foldable material at fold positions, to guide the folding, to form a coin inclosure, frame of folds, and sections of foldable material, to hold the coin inclosure in position, adapted to hold coins or other similar objects.

It is another object of the invention to provide a carrier that will hold the coins in approximately the center of the infolded carrier to facilitate handling, particularly in the cancellation of stamps and other machine handling in the postal system.

It is the still further object of the invention to provide a coin carrier which will be simple in construction and efficient and certain in use, which will carry one or more coins, or other similar objects, by means of a folded and adhesively secured coin inclosure, infolded at approximately its center, to hold safely and securely coins, or other similar objects, while being transported by the postal or other carrier systems.

A coin carrier constructed in accordance with the present invention is described in the following specification and shown in the accompanying drawing, I wish it understood, however, that the invention may be embodied in other forms than that which is described and shown, and that changes may be made in the details of construc-

tion of the embodiment shown, without departing from the scope of the invention, as defined in the appended claims.

In the drawing, Figure 1 is a plan of a sheet of foldable material which comprises the coin carrier. Figure 2 is a perspective view of the infolded carrier.

Like reference characters refer to like parts throughout the following specifications and the two figures of the accompanying drawing.

In the Figure 1, the lines 15, 16, 17, 18, 19, 20, 21, 22, 23, 24, and 25, mark the relative positions of the folds; 23, 4, 5, 6, 7, 8, 9, 10, 11, 12, and 13, represent sections of foldable material between the folds. The coin 1, is placed on section 6; sections 2, 3, and 4, are folded in a unit on fold 17 directly on top of the coin, which places sections 2, 3, and 4 in infoldment, folded against sections 5, 6, and 7, with the coin inclosure between sections 3 and 6; to further strengthen the coin inclosure adhesives 26, and 27, are applied by any of the conventional ways of applying adhesive, between sections 2 and 7, and sections 4 and 5; these sections are then infolded on fold 20, which places sections 2, 3, and 4; sections 5, 6, and 7, and a portion of sections 8, 9, and 10, in infoldment; sections 4, 5, and 10 are then infolded on folds 16, 18, and 21, in union, placing sections 4, 5, and 10, in infoldment with sections 3, 6, and 9, to form part of the coin inclosure, and supporting frame of folds, by the multiple folding of the foldable material; sections 2, 7, and 8 are likewise folded, in union, on folds 15, 19, and 22, placing sections 2, 7, and 8, in infoldment with sections 3, 6, and 9, to form the coin inclosure, and the supporting frame of infolds, by the folding of the foldable material in multiple layers, thus making the coin inclosure and its supporting frame of folds and sections of foldable material. Sections 11 to 13 are infolded around this formed coin inclosure and supporting frame of infolds by folds at 23, 24, and 25, to make a complete coin carrier, with a coin inclosure, supporting frame of infolds and sections of foldable material. The last section, 13, of infoldment, may then be joined to section 11 by adhesive material, 28, or other approved conventional fastener or metal clip holder. When infoldment is placed in an envelope, or other inclosure of a suitable size, no fastener is required as the infoldment would be held in position by the envelope or other like outside covering.

In Fig. 2 the dotted lines show the relative positions of folds after infoldment; as the folds would come very close and directly over one another,

for simplicity of illustration each fold is shown by a separate dotted line.

Having thus described the invention, what is claimed is:

5. 1. A coin carrier consisting of a sheet of paper having four or more sections parallel to each other, the first three sections being adapted to be folded over one another, and then folded diagonally from the adjacent corners of the fourth 10 section to the opposite side of the three-section infoldment leaving a space at the center for a coin pocket, and held in a central position of and folded on to the fourth and additional sections, adaptable as a coin carrier envelope inclosure, as 15 shown and described.

2. A coin carrier as described herein comprised of an oblong sheet of paper folded crosswise into four or more unequal sections, two parallel sections of a width required for a coin pocket being 20 gummed at intervening points to form a coin inclosure at the center of the two sections, this infoldment being then folded on to a third section

to inclose the coin pocket, and the three sections being then folded, as a unit, diagonally from the corners of the fourth section to the other edge of infoldment at the gummed edge of coin pocket, and then folded on to fourth and other sections, 5 substantially as shown and described.

3. A coin carrier consisting of a folding oblong sheet of paper comprised of four sections folded across the short way in parallel positions, two sections being of a suitable size to make a coin pocket by folding them on one another, then folding onto a third section which is of a suitable size to hold first two sections at the central part of a fourth envelope-size section, then folding the three folded sections in union at angles from the two adjoining corners of the fourth section to the top edge of three-section enfoldment making the form of a flat-top pyramid with a coin pocket at the vertex, and then folding onto the fourth envelope-fitting section, substantially as described. 10 15 20

HARRY C. BALLER.
